(57) **CLAIM**

The ornamental design for a portion of ferrule for optical fiber connector, as shown and described.

DESCRIPTION

FIG. 1 is a front view of a portion of ferrule for optical fiber connector showing our new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a perspective view thereof;

FIG. 8 is a front view of a second embodiment of our new design;

FIG. 9 is a rear view thereof;

FIG. 10 is a top view thereof;

FIG. 11 is a bottom view thereof;

FIG. 12 is a left side view thereof;

FIG. 13 is a right view thereof; and,

FIG. 14 is a perspective view thereof.

A portion of the claimed design is darkened to indicate the color black. The remaining portion of the claimed design indicates the color white.

The broken lines represent environmental subject matter and form no part of the claimed design.
